M. McCANN

POWER TRANSMITTING MECHANISM

Filed June 8, 1922

UNITED STATES PATENT OFFICE.

MICHAEL McCANN, OF GLENMORE, NEW YORK, ASSIGNOR TO FREDERICK OSANN COMPANY, A CORPORATION OF NEW YORK.

POWER-TRANSMITTING MECHANISM.

Application filed June 8, 1922. Serial No. 566,783.

To all whom it may concern:

Be it known that I, MICHAEL McCANN, a citizen of the United States, and resident of Glenmore, in the county of Queens and State 5 of New York, have invented certain new and useful Improvements in Power-Transmitting Mechanisms, of which the following is a specification.

This invention relates to power transmitting devices and has particular reference to 10 a mechanism for transmitting power adapted for use on sewing machines.

The object of the invention is to provide a simple, practical, novel and generally improved friction drive or power-transmitting mechanism adapted to be secured underneath a sewing machine table or work bench for transmitting power from a motor to the sewing machine or other mechanism on the 20 work bench.

Another object of the invention is to provide a power transmitting mechanism for the purpose set forth adapted to be assembled and mounted as a single unit and 25 provided with the necessary adjusting means for obtaining maximum efficiency.

Other objects will appear as this specification proceeds while reference is had to the accompanying drawing in which—

30 Figure 1 is a front elevation of a power transmitting mechanism embodying the invention with parts omitted and parts broken away.

Figure 2 is an end view of the mechanism 35 looking from the left in Figure 1.

Figure 3 is a detail sectional plan view on line 3—3 of Figure 1 with parts broken away and parts omitted.

40 Figure 4 is a diagrammatic view illustrating the normal inactive positions of the driving and the driven member in the mechanism.

Figure 5 is a diagrammatic view illustrating the driving and the driven members 45 in operative active positions.

Referring first to Figure 4 the reference 50 numeral 6 denotes a driving member diagrammatically represented by the inner dotted circle, while the numeral 7 denotes a driven member represented diagrammatically by the outer dotted circle. Normally these two members are in the positions shown, that is the driving member may be

rotated or operated continuously, while the driven member remains inoperative. 55

When, however, motion is to be imparted to the driven member it is moved so as to engage the driving member eccentrically as shown in Figure 5.

In the preferred arrangement described 60 and illustrated herein, the inner driving member may be in the form of a motor operated friction pulley, and the driven member may be in the form of a hollow or cup shaped wheel having an interior driving or 65 friction surface adapted to engage the driving surface of the driving pulley. And of course, it is within the intended and legitimate scope of this invention, that the inner member may be driven by the outer member. 70

It will be seen from Figure 5 that this principle of frictional driving presents several notable advantages. Thus it is obvious, that although theoretically, two circles can engage each other at only one point, 75 practically the situation is quite different, and as a matter of fact, the two members 6 and 7 engage each other for quite a distance at that portion of the circles marked 8, thereby providing for firm non-slipping frictional 80 engagement while the members are running together. Another advantage is that in locating one member within the other, a material saving in space is effected.

In the preferred embodiment of my invention the inner driving member consists of a pulley 9, see Figure 3, provided with a friction band or member 10 firmly secured to the pulley which latter is carried by and 85 operated by a suitable prime mover, as for instance the electric motor indicated at 11.

The driven member consists of the hollow or recessed wheel 12 having an interior surface 13 adapted to be frictionally and 90 operatively engaged by the friction member 10 on the pulley 9 as is obvious. The wheel 12 is preferably integral with a two stepped belt unit comprising the smaller and the larger belt pulleys 15 and 16 respectively. A belt 17 may run over either of said pulleys 15 and 16. 95

A bearing sleeve 18 is preferably integral with the wheel and pulleys aforesaid, so that the members 12, 15, 16 and 18 constitute an integral driven unit. Said unit is 100 rotatably carried on a hollow shaft 19 which 105

has a head or disk 20 whereby said driving unit is retained on the shaft. The latter is clamped in a hanger 21 by means of a screw 22 in a well known manner. The hanger 21 is pivoted on the adjustable pivot screws 22, 22 provided with lock nuts 24, 24. 25 is an operating arm on said hanger and 26 is a treadle rod for operating the hanger, the shaft and the driven unit.

10 The pivot screws 22 are carried by a fixed brake yoke 27 provided with a vertical base 28 and a horizontal brake arm 29. The base 28 is secured to the base lug 30 by means of a bolt and nut 31, 32. The bolt passes through a slot 33 in the base lug 30 thus providing for vertical adjustment of the brake yoke.

In order to prevent the yoke from turning on the base lug, the yoke has a key 34 which slides in a groove 35 in the base, see Figure 3.

The numeral 36 denotes a brake lever which carries a brake shoe 37 of leather or other suitable material. The brake lever 25 is adjustably secured to the brake arm 29 by means of a bolt 38 and nut 39. The bolt passes through a slot 40 in the brake lever to permit of lateral adjustment of the brake shoe with respect to the wheel 12. In order 30 to prevent turning of the brake lever on the brake arm, the arm has a key 41 which slides in a way 42 in the lever.

The wheel 12 is kept in contact with the brake shoe 37 by a spring 43 which is seated in the yoke 27 and presses against the hanger 21 below the pivots 22, 22. The spring 43 thus urges the hanger with the shaft 19 and the driven unit to the right in Figure 2, or the spring, as stated, presses 40 the wheel 12 against the brake shoe 37.

The base lug 30 is preferably integral with the main base 44 to which the motor 11 is secured. The base 44 is secured on the underside of the work bench 45. The machinery to be driven by the belt 17 is mounted on top of the bench (not shown) and suitable provisions are of course made for running the belt 17 upwards through the bench to drive the machinery thereon. 45 The parts and details are not shown as they form no part of the invention. Neither is the usual treadle mechanism illustrated for pulling the treadle rod 26 downward. An oil cup 46 of usual design for lubricating 50 the shaft 19 and driven unit 12—16 is mounted on the end of the shaft, see Figure 1.

During the operation the motor will be kept operating and thus continuously rotate 60 the pulley 9, without, however, operating the driven unit, because, as seen in Figures 3 and 4, the wheel 12, that is the unit, is maintained in concentric relationship with the driving pulley by the spring 43.

65 This positioning of the driven unit is ob-

tained by vertical adjustment of the hanger 27 on the base lug 30, and by adjusting the brake lever 36 on the brake arm 29 as aforesaid.

When the pulleys 15—16 are to be rotated 70 to drive the belt 17, the treadle rod 26 is moved downwardly, whereby the hanger 21 through the operating arm 25 is swung downwardly and to the left in Figure 2 to move the wheel 12 into contact with the motor pulley 9 and away from contact with the brake shoe, when of course, the pulley 9 will drive the wheel 12 by frictional engagement and also rotate the pulley 15— or 16 to drive the belt which transmits the power to the 75 machinery, a sewing machine for instance, on the bench 45.

It will be noted that the entire mechanism may be manufactured and shipped as a unit ready to be attached to the work bench. The 80 device is compact, easily assembled, is very sturdy in construction and easily adjusted. When the operator lets go of the treadle the spring 43 instantly operates to move the wheel 12 into contact with the brake shoe to 85 stop rotation of the wheel.

I claim:

1. A self contained unitary power transmitting mechanism comprising in combination a base, a motor secured thereto, a driving wheel operated by said motor, a driving unit adapted to be operated by said driving wheel, a hanger for supporting said unit, a yoke for pivotally supporting said hanger, means for adjustably supporting said yoke on the said base, means carried by said yoke for automatically normally maintaining said hanger and driving unit in non-operative relation with said driving wheel and means for operatively engaging said driving wheel and unit. 95

2. A self contained unitary power transmitting mechanism comprising in combination a base, a motor rigidly secured thereto, a driving wheel operated by said motor, a belt driving unit, a rigid yoke, means for pivotally supporting said belt driving unit on said yoke, a brake member secured to said yoke, means interposed between the said base and the said belt driving unit for automatically maintaining the said two elements in normal non-operative relationship and simultaneously therewith maintaining said driving unit in contact with the said brake and means for operatively engaging said 100 driving unit and wheel. 115

3. A self contained unitary power transmitting mechanism including in combination a driving unit and a driven unit, which latter comprises rigid supporting means, a 120 brake secured thereto, a hanger pivoted on said rigid supporting means, a shaft in said hanger, a pulley on said shaft, means on said rigid supporting means for maintaining said pulley in contact with the said 125 130

brake, means for moving said pulley away from said brake and into operative relationship with the said driving unit and means for securing the said driving unit to the 5 said rigid supporting means.

4. In combination a base, a yoke adjustably mounted thereon, a brake member adjustably mounted on said yoke, a driving unit pivoted in the latter and provided with 10 a pulley having an interior driving surface, a motor secured to the said base, a driving wheel operated by said motor and adapted

to engage the said driving surface on the pulley, a spring for maintaining the said pulley in non-operative concentric relationship with the said wheel and in contact with the said brake member and means for operating said pulley into driving relationship with the said wheel. 15

Signed at 245 Seventh Ave., in the county 20 of New York and State of New York this 2nd day of June A. D. 1922.

MICHAEL McCANN.
